UNITED STATES PATENT OFFICE.

GUSTAF A. ANDERSON, OF BALTIMORE, MARYLAND, ASSIGNOR, BY MESNE ASSIGNMENTS, TO THE SYMINGTON COMPANY, A CORPORATION OF MARYLAND.

DRAFT RIGGING.

Application filed May 23, 1922. Serial No. 563,006.

To all whom it may concern:

Be it known that I, GUSTAF A. ANDERSON, a citizen of the United States, residing at Baltimore, in the State of Maryland, have 5 invented certain new and useful Improvements in Draft Rigging, and I do hereby declare the following to be a full, clear, and exact description of the invention, such as will enable others skilled in the art to which 10 it appertains to make and use the same.

My invention relates to draft rigging back stops adapted to be connected to and interposed between the center sills or draft sills of a railway car to provide means for receiving the buffing shocks to which the draft rigging is subjected in service, and transmitting them to the car underframe.

The principal object of the invention is to provide a strong, durable and simply constructed back stop in which the maximum strength value of the related parts is obtained with the minimum use of material, thereby providing a comparatively light weight back stop which can be readily attached to the car sills with small expenditure of labor.

The principal feature of the invention, generally stated, consists in forming a back stop with side walls adapted to be connected to the car sills and with the forward end wall integrally united to said side walls and arranged to form an abutment for a movable part of the draft rigging, and in bracing and supporting said end wall by means of intersecting horizontal and vertical webs united at their forward ends to the end wall and said side walls.

A further object of the invention consists in providing the back stop with side walls and with an end wall constituting an abutment for a movable part of the draft rigging, and in providing bracing means for the end wall, said bracing means including a transversely disposed horizontal web or flange uniting the end abutment of the side walls, said horizontal web being formed with reinforcing longitudinally disposed ribbed portions.

A further feature of my invention consists in providing the back stop with side walls and an end wall constituting an abutment for a movable part of the draft rigging, said end wall being braced against buffing shocks by means of a transversely arranged flange including an inverted

U-shaped or channel-shaped bracing web arranged longitudinally and centrally of the back stop and having a forwardly and upwardly inclined flange integrally connected near the upper end of said end wall abutment. 60

A still further object of the invention is to provide a back stop formed with side walls and oppositely arranged end abutment walls, each of said abutment walls being braced by substantially horizontally arranged transverse webs having portions thereof interrupted and ribbed to reinforce the same, said transverse webs being arranged in different horizontal planes, and adapted to be intersected respectively, by vertical centrally located webs longitudinally aligned and integrally uniting the abutment walls with the top and bottom portions respectively of the back stop. 70

Other features of the invention residing in the construction and arrangement of the structural parts, will hereinafter appear.

In the drawings illustrating the invention, the scope whereof is pointed out in the 80 claims:

Figure 1 is a view partly in plan and partly in horizontal section of a portion of the center sills or draft sills of a railway car showing a back stop involving the invention applied thereto, a portion of the draft rigging being shown associated with the back stop. 85

Figure 2 is a vertical longitudinal sectional view of the back stop, detached from 90 the car frame.

Figure 3 is a transverse sectional view on the line 3—3 of Figure 2.

Figure 4 is a transverse sectional view on the line 4—4 of Figure 2. 95

Figure 5 is a view partly in plan and partly in horizontal section of a modified form of back stop embodying my invention.

Figure 6 is a vertical longitudinal sectional view of the form of back stop shown 100 in Figure 5.

Figure 7 is a view partly in plan and partly in horizontal section of still another form of back stop embodying my present invention. 105

Figure 8 is a vertical longitudinal sectional view through the back stop illustrated in Figure 7.

Referring to the drawings in which similar reference characters designate corre- 110

sponding parts in the several views and more particularly to Figure 1, I have shown my improved back stop 1 interposed between and connected to the center sills or draft sills 2—2 by means of rivets 3. The rear end of the yoke 4 is cooperatively associated with the back stop, the cushioning mechanism of the draft rigging being diagrammatically indicated by the dot and dash lines.

10 The back stop 1 is formed with longitudinally extending side walls 5 adapted to engage the inner faces of the adjacent car sills, each side wall being provided with a plurality of spaced horizontally extending rows of openings for receiving the attaching rivets 3 whereby the structure can be firmly connected to the car sills.

15 The end wall 6, positioned so as to be termed the forward end wall herein, is integrally connected to the side walls 5, and is adapted to afford an abutment for a movable part of the draft rigging in resisting buffing shocks. The outer ends of the side walls are preferably curved at the corners 20 and the outer side portions of the end wall 6 are slightly inclined as at 7, said inclined portions joining the end wall, as shown, to provide a maximum centrally located buffing face on said end walls 6.

25 30 A transverse flange or web 8 unites the side walls of the casting, and also the end wall 6 and the closed upper end of the center thimble 9. This transverse wall is of irregular contour, it being shown in the present embodiment of my invention as comprising a centrally inverted U-shaped or channel portion, the top part 10 thereof being arranged in a higher horizontal plane than the portions 11 of said web or flange. The 35 horizontal portions 11 join the vertical flanges 12 of the channel portion, the vertical flanges extending below the plane of the web portions 11, as clearly shown in Figure 4. The upper portion 10 of the inverted 40 U-shaped channel is forwardly and upwardly inclined, as shown in Figure 2, and is designed to join the forward end wall 6 at a point near the upper edge thereof. The irregular forming of the transverse flange or 45 web 8 whereby portions thereof lie in different or varying planes, permits of the ready insertion of the rivets through the intermediate row of openings. In addition, it 50 will be obvious that means of a greater reinforcing value can be centrally located in the rear of the forward end wall to absorb the 55 direct shocks through the rear of the yoke.

60 The vertical reinforcing flange or web 13 is designed to brace the forward end wall 6, said flange being located centrally and longitudinally of the casting and uniting the forward end wall 6 to the center thimble. The vertical flange 13 also intersects the portion 10 of the inverted U-shaped 65 channel formed in the transverse flange, and

units the top portion 14 of the casting with the base plate or floor portion 15 thereof. The portion of the vertical flange beneath the transverse web is indicated by the numeral 16, said portion adjoining the base plate 15 and being cut away as shown. The portion above the transverse flange is indicated by the numeral 17, said portion constituting a longitudinal rib joining the top portion 10 of the U-shaped channel.

70 75 The base plate or floor portion 15 of the casting is preferably cut away, as indicated at 18, and is provided adjacent its side edges with inclined portions 19 which latter are designed to overlie and conform to the adjacent flanges of the center sill or draft sills.

80 85 The side walls 5 are preferably extended rearwardly and offset from the horizontal, said extensions terminating in stop members 21 between which is arranged an end wall or abutment 22 of relatively smaller size and less height than the end wall 6 described herein as the forward end wall. The end wall 22 is braced by means of a plurality of longitudinally aligned ribs or flanges, the central flange 23 lying parallel to the side walls 5, and the web or flange 24 being slightly inwardly inclined from the center thimble as best shown in Figure 1. 90 The inclined flanges 24 are substantially preferably continuations of the parallel side or vertical flanges 12 of the channeled transverse web, but are relatively shallow in height and are brought inwardly at their 95 ends which join the end wall 22. The central flange 23 extends from the base plate and has an upper portion joining the top portion 14 of the casting, as shown. Obliquely arranged flanges 25 extend inwardly from the side wall extensions and are 100 designed to unite the end wall 22 with the side walls 5. The flanges 25 merge into the end wall 22 at or about the junction of the inwardly inclined flanges 24 and said end 110 wall.

115 120 A horizontal or transverse flange or web 26 connects the extensions of the side walls, said web intersecting the vertical flanges or webs 23 and 24, as clearly shown in Figure 3, thereby forming substantially a ribbed reinforcing means for said transverse flange. The stop portions 21 are braced by a plurality of longitudinally arranged ribs 27, said ribs serving to unite the end wall extensions and said stop portions. The intermediate ribs are joined by the obliquely disposed flange 25.

125 130 The portion of the base plate on the side of the casting just described is cut away as shown, extending stop portions of the casting serving as guiding means in some cases for portions of the draft rigging mechanism. The transverse vertical web 28 unites the side wall members intermediate the re-

spective end walls of the casting, said transverse vertical wall intersecting the center thimble. Rivet openings 29 are formed in the floor or base plate.

5 A draft rigging constructed in accordance with my present invention provides a combined back stop and center filler member in which an advantageous arrangement of the integrally joined flanges or ribs serves to effectively resist buffing shocks or blows and transmit them to the associated car framing without distortion or deformation of the casting. I provide in substance a centrally located channel or U-shaped portion with the respective portions of the transverse flange in varying planes upon either side of the intermediate vertical web 28, so as to provide space for the insertion of the intermediate row of rivets, and to also provide for increased bracing means adjacent the forward end wall 6.

In Figures 5 and 6 of the drawings, I have shown a modified form of the invention in which the centrally located channel or U-shaped portion of the casting is formed with inwardly converging vertical flanges 30, said flanges uniting the center thimble 31 to the forward end wall 32, as shown. Similarly, the vertical ribs or flanges 33 uniting the opposite end wall 34 to the center thimble 31 are also inwardly inclined toward the center thimble, the said opposite end wall 34 being shown straight and transversely connecting the side walls of the casting. Diagonal portions 35 serve to brace the extensions 36 of the side walls and the opposite end wall 34. A transverse vertical web 37 unites the side walls intermediate the opposite end walls, said vertical transverse wall intersecting the center thimble, as shown.

The modified form of back stop casting shown in Figures 7 and 8 includes a channel or U-shaped portion 38 adapted to brace the forward end wall 39, the inner ends of the channel portion terminating and uniting the intermediate transverse vertical web 40 with said end wall, as in the preferred embodiment as hereinbefore described. The side vertical flanges or ribs of the U-shaped channel portion are in this present modification parallel with the side walls, as shown. The opposite end wall 41 is shown as straight and transversely connects the side walls of the casting. A horizontal transverse flange 42 is provided on the upper and lower faces thereof with vertical ribs or flanges 43, said ribs being arranged in parallel with the side walls of the casting and uniting the upper portions 44 and the lower base plate portion 45, as clearly shown in Figure 8. Diagonal bracing webs 46 unite the side wall extensions and the opposite end wall 41.

65 It will be apparent that by means of the

internal flanges and ribs provided on a back stop constructed in accordance with my invention, that the casting is so reinforced that all stresses to which it may be subjected in service are amply resisted by sufficient sections of metal so economically arranged that the casting, while possessing great strength, is comparatively light in weight and is, moreover, a simple casting both to mold and cast.

70 To the reversible feature of my improved backstop I make no claim, the same being fully set forth and claimed in a co-pending application of Ira Orville Wright, Serial No. 525,981, filed December 30, 1921 now 80 Patent No. 1,458,792, dated June 12, 1923.

75 I claim:—

1. A back stop casting for railway draft rigging involving spaced side walls adapted to be connected to spaced car sills, a forward end wall united to the side walls and adapted to form an abutment for a movable part of the draft rigging, and a transverse web uniting said side walls and forward end wall, said transverse web having a centrally located channel portion formed of horizontal and vertical flanges adapted to brace said end wall.

80 2. A back stop casting for railway draft rigging involving spaced side walls adapted to be connected to spaced car sills, a forward end wall united to the side walls and adapted to form an abutment for a movable part of the draft rigging, and a web provided with a longitudinally extending U-shaped portion and uniting said side walls and forward end wall.

85 3. A back stop casting for railway draft rigging involving spaced side walls adapted to be connected to spaced car sills, a forward end wall united to the side walls and adapted to form an abutment for a movable part of the draft rigging, and a web provided with a channel shaped portion and uniting said side walls and forward end wall, the horizontal portion of said channel-shaped portion being forwardly and upwardly inclined.

90 4. A back stop casting for railway draft rigging involving spaced side walls adapted to be connected to spaced car sills, a forward end wall united to the side walls and adapted to form an abutment for a movable part of the draft rigging, and a transverse web having a centrally located channel portion, said channel portion extending longitudinally of the casting and joining the forward end wall.

95 5. A draft rigging back stop casting involving spaced side walls adapted to be connected to spaced car sills, a forward end wall united to said side walls and adapted to form an abutment for a movable part of the draft rigging, a transverse web member uniting said side walls and forward end

wall, said web member having a plurality of horizontal portions arranged in one plane adjacent the side walls, another horizontal portion disposed in another plane intermediate the side walls, and vertically arranged webs uniting said horizontal portions.

6. A draft rigging back stop casting involving spaced side walls adapted to be connected to spaced car sills, a forward end wall united to said side walls and adapted to form an abutment for a movable part of the draft rigging, a transverse web member uniting said side walls and forward end wall, said transverse web member having a plurality of horizontal portions arranged in one plane, another horizontal portion disposed in another plane, and vertically arranged webs uniting said horizontal portions, said vertical webs being arranged parallel to the side walls and having portions extending below the horizontal portions arranged in the lowermost plane.

7. A draft rigging back stop casting involving spaced side walls adapted to be connected to spaced car sills, a forward end wall united to said side walls and adapted to form an abutment for a movable part of the draft rigging, a transverse web member uniting said side walls and forward end wall, said transverse web member having a plurality of horizontal portions in one plane, another horizontal portion in another plane, top and bottom portions for said casting, vertical webs uniting said horizontal portions, and a centrally located longitudinal rib intersecting one of said horizontal portions and being adapted to unite the top and bottom portions of the casting.

8. A draft rigging back stop member involving spaced side walls adapted to be connected to spaced car sills, a forward end wall united to said side walls and adapted to form an abutment for a movable part of the draft rigging, a transverse web uniting said side walls and forward end wall, said transverse web having a longitudinally extending centrally located channel portion adapted to brace said forward end wall, and a vertical flange intersecting said channel portion.

9. A draft rigging back stop member involving spaced side walls adapted to be connected to spaced car sills, a forward end wall united to said side walls and adapted to form an abutment for a movable part of the draft rigging, a transverse web uniting said side walls and forward end wall, said transverse web having a centrally located channel portion extending therefrom longitudinally of the stop member and adapted to brace said forward end wall, top and bottom portions provided on said casting, and a vertical longitudinally arranged flange uniting said top and bottom portions, said vertical longitudinally arranged flange in-

tersecting the channel portion of said transverse web.

10. A draft rigging back stop comprising side walls adapted to be connected to spaced car sills, a forward end wall united to said side walls and adapted to provide an abutment for a movable part of the draft rigging, a horizontal transverse web formed with an intermediate longitudinally extending channel portion and adapted to unite the side walls and brace said forward end wall, said transverse web extending rearwardly of the channel portion, a vertical transverse web intersecting said intermediate channel portion and horizontal transverse web, and an opposite end wall uniting the side walls and said horizontal transverse web.

11. A draft rigging back stop comprising side walls adapted to be connected to spaced car sills, a forward end wall united to said side walls and adapted to provide an abutment for a movable part of the draft rigging, a horizontal transverse web formed with an intermediate channel portion and adapted to intersect and brace said forward end wall, said transverse web extending rearwardly of the channel portion, a vertical transverse web uniting said side walls, a vertical longitudinally arranged web intersecting said intermediate channel portion, an opposite end wall uniting the side walls and intersecting the rearwardly extending portion of the horizontal transverse web, a plurality of inwardly converging ribs extending from said transverse vertical web and disposed above and below the horizontal transverse web, said inwardly converging ribs intersecting the opposite end wall for reinforcing the same.

12. A draft rigging back stop comprising side walls adapted to be connected to spaced car sills, a forward end wall united to said side walls and adapted to provide an abutment for a movable part of the draft rigging, a horizontal transverse web formed with an intermediate channel portion and adapted to intersect and brace said forward end wall, said horizontal web extending rearwardly of the channel portion, a vertical transverse web uniting said side walls, a vertical longitudinally arranged web intersecting said intermediate channel portion and extending rearwardly therefrom, an opposite end wall uniting the side walls and intersecting the rearwardly extending portion of the horizontal transverse web, said end wall having obliquely disposed portions, and a plurality of vertical ribs extending rearwardly from said transverse vertical web and projecting above and below said transverse horizontal web, said ribs intersecting the obliquely disposed portions at their points of juncture with said opposite end wall.

13. A draft rigging back stop member in-

volving spaced side walls and a forward end wall united to said side walls and adapted to form an abutment for a movable part of the draft rigging, a vertical transverse web 5 uniting said side walls, a horizontally arranged transverse web formed with an intermediate channel portion joined to said vertical transverse web, a plurality of inwardly converging ribs extending from said vertical transverse web, another horizontally arranged transverse web intersecting said ribs and uniting the side walls, and an opposite end wall adapted to be reinforced 10 by said inwardly converging ribs and said second mentioned horizontal transverse web, 15 said opposite end wall uniting the side walls.

14. A draft rigging back stop member involving spaced side walls and a forward end wall united to said side walls and adapted to 20 form an abutment for a movable part of the draft rigging, a vertical transverse web uniting said side walls, a horizontally arranged transverse web formed with an intermediate channel portion joined to said vertical transverse web, a plurality of inwardly converging ribs extending from said vertical transverse web, another horizontally 25 arranged transverse web intersecting said ribs and uniting the side walls, and an op- 30 positively arranged end wall adapted to be re-

inforced by said ribs and second mentioned horizontal transverse web, said opposite end wall being provided with obliquely disposed side portions adapted to unite the side walls. 35

15. A draft rigging back stop member involving side walls adapted to be connected to spaced car sills, a forward end wall united to said side walls and adapted to form an abutment for a movable part of the draft rigging, and a plurality of longitudinally disposed horizontal and vertical webs or flanges adapted to form a channel shaped portion for bracing said end wall. 40

16. A draft rigging back stop involving side walls adapted to be connected to spaced car sills, a forward end wall united to said side walls and adapted to form an abutment for a movable part of the draft rigging, an opposite end wall uniting said side walls, a horizontal transverse web having a plurality of horizontal and vertical intersecting ribs forming a U-shaped channel portion adapted to reinforce said forward end wall, and a plurality of vertical ribs forming substantially longitudinal continuations of the vertical ribs forming the U-shaped channel portion for reinforcing the opposite end wall. 45

50 In testimony whereof I affix my signature.

GUSTAF A. ANDERSON.
